UNITED STATES PATENT OFFICE.

ALBERT H. STEBBINS, OF LOS ANGELES, CALIFORNIA.

CLASSIFIER.

Application filed December 24, 1926. Serial No. 156,847.

This invention relates to classifiers of the type in which the materials passing downwardly within a treatment chamber are subjected to the action of air currents adapted to separate the finer particles from the coarser particles.

In employing classifiers of this general type it is difficult to effect a thorough treatment of the materials through the use of air blasts alone, or through air exhausts alone, and if the materials to be separated are relatively fine it is necessary to subject them time and time again to the action of the separating air currents.

15 The present invention is therefore directed to a multiple treatment classifier which is so constructed that materials passing downwardly through the treatment chamber are subjected repeatedly to the separation action 20 of different air currents to extract the lighter from the heavier particles, and also to a construction for employing both suction and blast forces in effecting the separation of the materials.

25 One of the features of the present invention resides in a classifier casing which is adapted to be supported in an upright position so that the materials to be treated may pass downwardly therein under the influence of gravity, and in means for directing air jets across the path of the materials from the opposite sides of the casing to deflect the materials back and forth from one side of the casing to the other as they move 30 downwardly therein.

Another feature of the invention resides in means for removing the lighter particles that remain suspended in the air from the casing by exhausting them therefrom in a 40 direction at right angles to the air jets, and also in settling chambers that are adapted to return to the casing the particles that settle in said chambers.

Another feature of the invention resides 45 in the novel arrangement of parts for supplying air under pressure to the treatment chamber and for exhausting air therefrom, and also in the means for introducing air from the atmosphere into the casing.

50 Other features of the invention and novel combination of parts in addition to the above will be hereinafter described in connection with the accompanying drawings, which illustrate one good practical form of the invention.

In the drawings:

Fig. 1 is a side elevation of a classifier constructed in accordance with the present invention;

Fig. 2 is a sectional view taken on the 60 line 2—2 of Fig. 1;

Fig. 3 is a top plan view of the construction shown in Fig. 1;

Fig. 4 on an enlarged scale is a perspective view of the upper portion of the classifier shown in Fig. 1; the walls of the classifier being partly broken away to show the internal construction; and

Fig. 5 is a sectional view taken on the line 5—5 of Fig. 2.

In the embodiment of the invention shown the separation of the materials is effected in the central casing 10 which is adapted to be supported in an upright position so that the materials to be treated will pass downwardly within the casing under the influence of gravity. The casing 10 is shown as square in cross section and as having one pair of opposite walls 11 and a second pair of opposite walls 12. The casing is preferably made square or rectangular in cross section in order to better accommodate the air blast pipes 13 which extend lengthwise of the side walls 11 of the casing, and to accommodate the dust extracting chambers 14 which are arranged lengthwise of the side walls 12 of the casing, as will be hereinafter more fully explained.

The materials to be treated may be delivered to the upper end of the casing 10 by the feed hopper 15 having the central discharge opening 16, and the rate at which the materials are supplied to the treatment chamber by the hopper 15 may be controlled by adjusting the sliding gate 16a.

Air under pressure is supplied to the air blast pipes 13 by a blast fan or the like 17, and the upper ends of the pipes 13 are connected to the fan 17 by the branch pipes 18, as best shown in Fig. 3. The strength of the air supplied to the blast pipes 13 may be controlled by adjusting the sliding gate 19 (see Fig. 1).

As the materials being treated pass downwardly within the casing 10 they are deflected back and forth from one side wall of the casing to the other by air jets which are directed transversely of the casing 10 from the opposite side walls 11 thereof, and to this end in the construction shown each side wall 11 of the casing is provided with a large number of slots or air discharge noz-

zles 20 which are conveniently formed by bending portions of the walls adjacent the slots 20 inwardly, as indicated by 21. The discharge slots 20 in the opposite walls 11 5 are preferably arranged in staggered relation to each other, as best shown in Fig. 2, wherein it will be seen that the air from one nozzle is not directed against the air blast from an opposite nozzle, but strikes the wall 10 11 of the casing between a pair of adjacent nozzles. As a result of the construction just described it will be seen that the materials being treated will be deflected back and forth a number of times while they pass 15 downwardly within the treatment casing 10. The number of air discharge nozzles 20 employed, and the length of the treatment casing 10 will depend largely upon the nature of the materials being treated. If the classifier is designed to treat relatively coarse materials a comparatively few discharge nozzles 20 may suffice to effect the desired separation, but if the classifier is to be employed to separate fine, dust-like particles, it will be 20 necessary to subject the materials time and time again to the separating action of the air blasts delivered by the nozzles 20.

The heavier materials which pass downwardly within the casing 10 to the lower end 25 thereof will be collected in the discharge spout 22 from which they may be withdrawn from time to time by opening the discharge gate 23. It is necessary to remove from the casing 10 the finer particles that remain suspended within the air, and this is accomplished, in accordance with the present invention, by providing a large number of air discharge openings 24 within the opposite side walls 12 of the casing. It is desirable 30 to introduce the air withdrawn from the casing 10 into settling chambers in order that the larger particles that may escape through the openings 24 will have an opportunity to settle, and to this end the settling compartments 14 above mentioned are provided. These compartments are conveniently constructed by providing the classifier casing with the side walls 25 which extend laterally from the treatment casing 10 to the air exhaust pipes 26 mounted at each side of the casing 10 in spaced relation to this casing, as best shown in Fig. 1. Within the chambers 14 formed between the spaced side walls 25 are mounted the inclined floor plates 27 35 between which are formed the settling compartments and the arrangement of these floor plates is such that the materials that settle within the compartments will slide down these inclined plates to be returned to the 40 casing 10 for further treatment.

The air exhaust pipes 26 above mentioned are preferably made square or rectangular in cross section, as will be apparent from Fig. 4, and air is exhausted from each of these 45 pipes by connecting the upper end of each

pipe 26 to a conduit 28 which may lead to a suction fan, not shown. Air is exhausted from the upper portion of each settling chamber 14 by forming the openings 29 in the inner wall 30 of each pipe 26, as best 50 shown in Fig. 4, the arrangement being such that the suction produced within the pipes 26 will cause the air in which the lighter particles may be suspended to pass through the openings 24 into the settling chambers 14, and this air will travel upwardly within the settling chambers to escape therefrom through the discharge slots 29 into the exhaust pipes 26.

If air is exhausted from the treatment 55 casing 10 by the suction pipes 26 more rapidly than it is supplied to this casing by the blast pipes 13 a partial vacuum may be produced within the casing 10, which will materially affect the separating operation. It may 60 therefore be desirable to provide means for introducing air from the atmosphere into the casing 10 and this is accomplished, in accordance with the present invention, by the construction shown, whereby air is led 65 into the settling compartments adjacent the lower end of each inclined floor plate 27, the arrangement being such that the air introduced from the atmosphere will pass upwardly through the materials sliding down the inclined floor plates 27, to assist in the separation of these materials. In order to introduce air from the atmosphere into the classifier casing near the lower end of each inclined floor 70 75 80 85 90 95 100 105 110 115 120 125 130 plate 27 an air guide plate 31 is disposed adjacent the lower end of each floor plate to provide the air passage 32 at the under face of each plate 27, and air is admitted to the air passage 32 through the opposite side walls 25 of the casing by providing these side walls with the air inlet holes 33. The upper portion of each plate 31 is rounded as indicated by 34 to close the upper end of each air passage 32. The lower end of each plate 31, it will be noted, 120 extends into an opening 24 of a side wall 12, the arrangement being such that the materials which are delivered by the floor plate 27 to the air guide plate 31 will be directed by the latter through an opening 24 into the 125 casing 10 for further treatment.

It will be apparent from the foregoing description, when read in connection with the drawings, that air under pressure is supplied to the opposite walls 11 of the casing 10 by the air blast pipes 13 to produce the air jets above described which deflect the materials back and forth as they move downwardly within the casing 10, and it will be understood that the lighter particles 130 which remain suspended in the air within the casing 10 are withdrawn therefrom through the discharge slots 24 into the settling compartments 14 so that the particles that settle within these compartments will 135

be returned to the casing 10 for further treatment. Such particles as may settle within the suction pipes 26 will collect in the discharge hoppers 35 at the lower end thereof and from which the materials may be withdrawn from time to time. The air blast pipes 13 are preferably provided with the discharge openings 36 at their lower ends so that these pipes may be blown out 10 from time to time by opening the gates 37 at the lower ends of these pipes.

What is claimed is:—

1. A classifier comprising in combination, an upright casing, means for delivering the 15 materials to be treated to the upper portion of the casing to pass downwardly therein under the influence of gravity, air blast nozzles provided along the opposite sides of said casing and adapted to direct air currents across the casing from one wall to adjacent the other wall so that they will intersect the path of the materials moving downwardly within the casing from its opposite sides, and means for removing from 20 the casing the lighter particles that remain suspended in the air.

2. A classifier comprising in combination, an upright casing, means for delivering the materials to be treated to the upper portion 30 of the casing to pass downwardly therein under the influence of gravity, means for directing jets of air into the casing from the opposite sides thereof and arranged in staggered relation to each other so that the 35 materials passing downwardly within the casing will be deflected back and forth from one side wall of the casing to the other, and means for removing from the casing the lighter particles that remain suspended in 40 the air.

3. A classifier, comprising in combination, an upright, casing, means for delivering the materials to be treated to the upper portion 45 of the casing to pass downwardly therein, means for introducing jets of air into the casing from the opposite sides thereof at intervals along the path of the materials moving downwardly in the casing to cause the air jets to intersect said path from its 50 opposite sides, and means for exhausting air from the casing at points between the adjacent air jets.

4. A classifier, comprising in combination, an upright casing having four opposite side 55 walls, means for delivering the materials to be treated to the upper portion of the casing to pass downwardly therein, means for introducing jets of air into the casing from one pair of opposite side walls to cause the air 60 jets to intersect the path of the materials moving downwardly within the casing, and means for removing air from the casing through openings formed in the second pair of opposite side walls.

5. A classifier comprising in combination,

a relatively long slender casing adapted to be supported in an upright position, means for delivering the materials to be treated to the upper portion of the casing to pass downwardly therein, a series of air jets 70 mounted in close proximity to each other in a pair of opposite walls of the casing throughout the length of the casing and adapted to deflect the material passing downwardly within the casing back and forth 75 from one side wall to the other, and means for removing from the casing the lighter particles that remain suspended in the air.

6. A classifier comprising in combination, an upright casing having four opposite side 80 walls, means for delivering the materials to be treated to the upper portion of the casing to pass downwardly therein, a pair of air blast pipes arranged along two of the opposite walls of the casing and provided with 85 air apertures for directing air jets into said casing from its opposite side walls and a pair of air exhaust pipes extending lengthwise of the two remaining walls of the casing and provided with air openings for 90 exhausting air from the casing at points between said air jets.

7. A classifier comprising in combination, an upright casing, means for delivering the materials to be treated to the upper portion 95 of the casing to pass downwardly therein under the influence of gravity, means for introducing jets of air into the casing from the opposite sides thereof at a multiplicity of points along its length, means for forming a series of settling chambers along said casing and provided with inclined floors for directing the particles that settle in the chambers back into said casing for further treatment, and means for removing from 105 said chambers the lighter particles that remain suspended in the air.

8. A classifier comprising in combination, an upright casing, means for delivering the materials to be treated to the upper portion 110 of the casing to pass downwardly therein under the influence of gravity, means for introducing jets of air into the casing to intersect the path of the materials moving downwardly within the casing, and means for 115 exhausting air from said casing through a side wall thereof in a direction at right angles to the path of the air jets, including settling chambers along said casing and provided with inclined floors for directing the particles that settle in the chambers back into the casing for further treatment.

9. A classifier comprising in combination, an upright casing, means for delivering the materials to be treated to the upper portion 125 of the casing to pass downwardly therein under the influence of gravity, means for introducing jets of air into the casing from the opposite walls thereof to intersect the path of the materials moving downwardly 130

within the casing, and means for exhausting air from said casing through opposite side walls thereof in a direction at right angles to the path of the air jets, and including 5 settling chambers along said casing and constructed to return to the casing the heavier particles that settle in the chambers.

10. A classifier comprising in combination, an upright casing, means for delivering the materials to be treated to the upper portion of the casing to pass downwardly therein under the influence of gravity, means for introducing jets of air into the casing to intersect the path of the materials moving 15 downwardly within the casing, means for exhausting air from the casing through a side wall thereof in a direction at right angles to the path of the air jets, including settling chambers along said casing and provided with inclined floors for directing the particles that settle in the chambers back 20 into the casing, and means for introducing air into the casing at the lower end of each inclined floor to pass upwardly through 25 the materials sliding along the floors.

11. A classifier comprising in combination, an upright casing, means for delivering the materials to be treated to the upper portion of the casing to pass downwardly therein 30 under the influence of gravity, means for introducing jets of air into the casing from a pair of opposite side walls thereof to intersect the path of the falling materials,

means for exhausting air from the casing through opposite side walls thereof in a direction laterally to the air jets, including 35 settling chambers along said casing and provided with inclined floors for directing the particles that settle in the chambers back into the casing for further treatment, and 40 means for introducing air from the atmosphere into the casing at a multiplicity of points lengthwise of the same.

12. A classifier comprising in combination, a four-sided casing constructed to be supported in an upright position and provided with an air conduit extending along each side of the casing, means for delivering the materials to be treated to the upper portion of the casing to pass downwardly therein 45 under the influence of gravity, two of said conduits positioned at the opposite sides of said casing being provided with a series of air apertures disposed lengthwise of the casing to produce air jets across the casing 50 to intersect the path of the falling materials, means for delivering air under pressure to the two conduits, said remaining pair of conduits being provided with a series of apertures disposed lengthwise of the casing 55 for exhausting air from the casing, and means for exhausting air from the two conduits last mentioned.

In testimony whereof, I have signed my name to this specification.

ALBERT H. STEBBINS.
